UNITED STATES PATENT OFFICE.

HERMAN F. W. SCHLECKSER, OF NEWARK, NEW JERSEY, ASSIGNOR TO
EASTWOOD & PARK, OF SAME PLACE.

DESIGN FOR A HANDLE FOR BUTTON-HOOKS OR SIMILAR ARTICLES.

SPECIFICATION forming part of Design No. 28,552, dated May 10, 1898.

Application filed March 9, 1898. Serial No. 673,273. Term of patent 3½ years.

To all whom it may concern:

Be it known that I, HERMAN F. W. SCHLECKSER, a citizen of the United States, residing at Newark, in the county of Essex and State of New Jersey, have invented and produced a new and original Design for Handles for Button-Hooks, &c.; and I do hereby declare the following to be a full, clear, and exact description of the invention, such as will enable others skilled in the art to which it appertains to make and use the same, reference being had to the accompanying drawing, and to letters of reference marked thereon, which forms a part of this specification.

The single figure of the drawing is a plan of a button-hook having a handle of my new design and is deemed sufficient for the purpose of illustrating the same.

The leading feature of my design consists in the conventionalized foliated scrolls outlining the edges of the handle and the raised ornamentation of the sides, as shown in the drawing.

At the smaller end of the handle the same is ornamented by long plain scrolls *a a* at each side of the longitudinal central line of the side of the handle, said scrolls having their ends curved outward and returned, as at *b b*. Between the divergent ends of said scrolls the handle is ornamented by a rose-shaped figure, and outside of each scroll *a a* and parallel thereto is a line of beading *d*. Adjacent to the divergent ends of the long scrolls *a a* are displayed at the opposite edges of the handle short foliated scrolls *f f*, having their concavities and turned ends facing inward toward

the longitudinal axis of the handle, the said scrolls inclosing or bordering a central open field *e*. Next in order along the edges of the handle is displayed an opposite pair of large foliated scrolls *g g*, the concave sides of which face toward the axis of the handle, said scrolls diverging toward the large end of the handle. Between the diverging ends of said large scrolls *g g* is a transverse scroll *h*, the concavity and turned ends of which face toward the large end of the handle. Adjacent to the convexity of said transverse scroll *h* a line *i* of rose-shaped ornaments extends transversely between the large divergent scrolls *g g* at the edges of the handle, and lying within the concavity of said transverse scroll is a rose-shaped ornament *j*. Beyond the large scrolls *g g* a pair of small foliated scrolls *k k* lie at the opposite edges of the handle, having their concavities and turned ends facing outwardly. Said small scrolls *k k* converge toward the end of the handle, where they closely approach each other, the space between being occupied by a shell-shaped ornament *l* at the tip of the handle.

What I claim as new is—

The design for a handle of a button-hook or similar article, substantially as herein shown and described.

In testimony that I claim the foregoing I have hereunto set my hand this 4th day of March, 1898.

HERMAN F. W. SCHLECKSER.
